UNITED STATES PATENT OFFICE.

LYLE H. FULTON, OF NASHVILLE, TENNESSEE.

SWITCH-POINT PROTECTOR.

Application filed April 21, 1927. Serial No. 185,595.

This invention relates to devices for protecting switch points from wear and the object of the invention is to provide a protector which will not only protect a switch point from wearing out (or dubbing off) at the pointed end, but also prevents the flanges of a locomotive or car wheels from splitting the points.

The invention consists in the provision of a head piece or protector adapted to be disposed against the web of a rail in advance of the switch point and clamped upon the rail, so as to cause the inward movement of the flange of the car wheel in advance of the switch point, and prevent the flange from striking the point of the rail.

My invention is illustrated in the accompanying drawings, wherein:

Figure 1 is a side elevation of a rail with my device applied thereto;

Figure 2 is a plan view;

Figure 3 is a section on the line 3—3 of Fig. 1.

Referring to these drawings, it will be seen that the head piece or protector 10 has a longitudinally rounded and vertically rounded outer face 11 and is recessed upon its inner face as at 12 and 13 so as to fit against the side face of the head or ball of the rail 30 and against the under face thereof on one side of the web. The base 14 of this head piece extends downward parallel to or in spaced relation to the web of the rail A. The outer face 11, it will be seen, is downwardly 35 and outwardly rounded and the upper edge of the head is disposed slightly below the upper face of the rail A. This protector may be of any suitable length, but preferably in actual practice will be made about from 40 five to six inches long. It is held in place by two bolts 15 which pass through elongated apertures in the shank 14 and through apertures in a filler block 16 which fits against the outside of the shank and fits beneath the head 10, the lower edge of this 45 filler block resting against the flange of the rail A and wedging against this flange. The head piece comprising the parts 10 and 14, is preferably made of the highest grade of 50 manganese steel while the filler block is preferably made of malleable cast iron. The head piece is made to fit all sizes or classes of rails that are most used today and fits an eighty, ninety, one hundred, or one hundred and ten pound rail. This head piece 55 will have as much or more steel in it as is in

the first six inches of the point B. This enables the protector or head piece to wear almost as long as the switch point will, for when the point wears back or off from six 60 to twelve inches, it is no longer used and is scrapped. The filler block is also to be of various lengths and sizes; for an eighty pound, ninety pound or any other desired weight of rail. It is to be made of malleable 65 or any other cheap iron as there is no strain or wear upon the filler block. This will cause a saving in steel.

It will be noted that in my device, the deflecting piece or head piece 10 is offset so 70 as to fit against the web of the rail as well as the head of the rail and the deflecting piece fits various types and weights of rail. My device when complete is relatively light and when the head piece wears out, it can be 75 scrapped without the necessity of scrapping the filler block and this means a saving of at least one-half to the consumer.

I claim:

1. A switch point protector or guard comprising a member fitting against the head of a rail and beneath said head and extending parallel to the web of the rail and adapted to be disposed in advance of a switch point, said member being tapered at its ends and having its outer face extending upward and inward and merging into the corner of the rail, and a filler block adapted to bear against the lower portion of said member and against the flange of the rail and be bolted 80 to the rail to hold the member in place.

2. A switch point protector or guard having a longitudinally extending head formed upon its inner face to fit against the side face of the head of the rail and beneath said head and having a portion extending downward parallel to the web of the rail, the outer face of the protector at its upper end being longitudinally rounded so as to provide relatively thin ends and being vertically 95 rounded downward and outward, and a filler block fitting beneath the head of said protector and extending downward parallel to the depending portion thereof and fitting against the flange of the rail, the protector 100 and the filler block being formed with bolt openings.

3. The combination with a rail and a switch point coacting therewith, a guard for the switch point disposed in advance thereof 110 comprising a member angular in cross section so as to provide a head fitting against

the side face of the head of the rail and beneath said head and extending downward parallel to the web of the rail, the head of this member being longitudinally rounded to provide tapered ends and being vertically rounded downward and outward, a filler block disposed beneath the head of said member and extending downward against the

depending portion thereof and resting at its lower end against the web of the rail, 10 and bolts passing through said filler block and said member and through the rail.

In testimony whereof I hereunto affix my signature.

LYLE H. FULTON.
